UNITED STATES PATENT OFFICE.

OSCAR WILLIAM ANDERSON, OF CHICAGO, ILLINOIS, ASSIGNEE TO ALEC J. GERRARD,
OF CHICAGO, ILLINOIS.

REINFORCED CONTAINER.

Application filed January 22, 1925. Serial No. 4,014.

To all whom it may concern:

Be it known that I, OSCAR WILLIAM ANDERSON, a citizen of the United States, residing at Chicago, in the county of Cook and State of Illinois, have invented certain new and useful Improvements in Reinforced Containers; and I do hereby declare the following to be a full, clear, and exact description of the invention, such as will enable others skilled in the art to which it appertains to make and use the same.

This invention relates to a bracing structure for shipping and other containing vessels and has for its object to provide a means of strengthening said vessels which will be certain in operation and less expensive to manufacture than those heretofore proposed.

With these and other objects in view, the invention consists in the novel details of construction and combinations of parts more fully hereinafter disclosed and particularly pointed out in the claims.

Referring to the accompanying drawings, forming a part of this specification, in which like numerals designate like parts in all the views:

Figure 1 is a perspective view partly broken away of a container provided with this invention;

Figure 2 is a cross sectional view of the parts shown in Figure 1;

Figure 3 is a cross sectional detail view of a portion of the parts shown in Figure 1; and

Figure 4 is a view taken on the line 4—4 of Figure 3 looking in the direction of the arrows.

1 indicates the sides, 2 the bottom and 3 the ends of a shipping or containing vessel made of wood, and 4 indicates a cellular structure with which said vessel is provided.

5 indicates vertically disposed end strips or pieces attached to the ends 3, and 6 indicates grooves or mortises with which the sides 1 are provided in order to receive the ends 7 of the transverse pieces 8, as shown. The sides 1 are composed of a plurality of pieces 9 and 10 in order to construct said sides of a cheaper grade of lumber, and likewise the ends 3 are composed of a plurality of pieces

11 and 12 in order that said ends may be less costly than when made of single pieces. In the same way, the bottom 2 of the container is made of a plurality of pieces 13, 14 and 15, for the sake of economy in construction.

As is well known in the art of wooden box manufacture, lumber is now so high that shipping boxes as well as containing receptacles are made of scrap material and other pieces of lumber which can only be sold for relatively low prices, and therefore it often becomes difficult to solve the problem as to how this cheaper grade of lumber can be so secured together in pieces as to form a strong and durable box and yet come within the commercial limits of cost.

By this invention, on the other hand, many of the difficulties heretofore encountered have been solved in the following way: The members 9 of the sides 1 are made of a width sufficiently great to extend up above the partition members 8, as shown, and just at the top edges of the partition members 8 holes 16 are made in each side member 9 through which wires 17 are passed. These wires 17 encircle the lower portion of the receptacle, including the side and bottom walls as well as the partition members 8 as illustrated, and their ends 19 and 20 are brought together under the bottom 3 of the box as clearly shown in Figure 2. That is to say, the box is turned bottom upward and a suitable wire tying machine such as that illustrated in the Gerrard & Wright patent, No. 1,456,127 dated May 22, 1923 is placed on the upturned bottom, whereupon the wire 17 is passed through the machine and the holes 16 on each side of the receptacle. The machine is next operated to first tension this wire almost to its breaking point or to a tension of say 300 or 400 pounds sufficient for the wire to bite into the corners of the box as illustrated at 22. The overlapping ends 19 and 20 of the wire are next twisted together as at 33, the wire cut off and the said ends tucked down underneath the main portion 17 of the said wire, all as will be clear from said Figure 2 and from the description in the above mentioned patent. One or more wires 17 may be thus passed around the box and secured in place, whereupon the box will not only be greatly strengthened and stiffened by the compression of said wires but the partition members 8 will be gripped and held firmly in place.

The advantages of the bracing structure thus produced will be appreciated when it is considered that the strains brought upon a box of this character tend to distort the structure and to permanently displace one

member relatively to another. For example, the box shown in Figure 1 might be dropped from a height on the corner 25, which would force or tend to force upwardly as seen in 5 Figure 1, the point 26 where the wire bites the box. But, the point 26 could not be displaced without straining the wire 17 longitudinally, and as the wire is enormously strong relative to the box structure to resist 10 these longitudinal strains, the displacement of the point 26 will be so effectually resisted that it will not take place to any appreciable extent. Tests have shown that before the point 26 can be thus displaced appreciably, the wire will actually bite into 15 or cut into the box and the pieces will often become broken. The same is true of any other displacement of the members of the box structure. The wires 17 in every instance will be strained in directions longitudinal 20 of their lengths and will thus resist with a tensile strength amounting to something like 135,000 pounds to the square inch. That is, the box will show a stiffness 25 or a resistance to distortion very much greater than could be attained by even a first-class grade of lumber. The result of thus permanently bracing the box with one or more wires 17 under tension is to impart 30 to a box made of an inferior grade of lumber a very much greater strength and a longer life than is possible with the same outlay of money when using only nails and other ordinary fasteners. Said wires 17 also 35 enable a person to use a still cheaper grade of lumber and produce a box that will stand the same tests as will a box made entirely of lumber at a much greater cost. In fact, many of the parts of the box such as the 40 sides and bottom, when provided with this invention, may be made of thinner pieces and of lower grade pieces than heretofore

and yet retain a standard of strength which could not be attained if the wires 17 were omitted.

By extending the side members 9 above the top edges of the partition members 8 and passing the wires 17 through said side members, said wires become a permanent part of the bracing structure, and they being secured in place under tension they exert a continual compressive action on the sides, bottom and partition members which firmly holds the parts together with the ends 7 of said members 8 disposed in said slots or mortises 6. So great is the tension placed upon the wires that they bite into the corners of the box sufficiently to be held permanently in place.

What is claimed is:—

1. In a wooden box, the combination of side and bottom walls; and a wire under tension forming a part of the bracing structure passing through said side walls over said bottom wall, over a portion of the inside of the box, and having its ends secured together.
2. In a wooden box, the combination of side walls provided with perforations, and a bottom wall; a wire under tension forming a permanent part of the bracing structure passing through said perforations over portions of said side walls, over said bottom wall, over a portion of the inside of the box, and having its ends twisted together.
3. In a wooden box, the combination of side walls, a bottom and a partition; a wire forming a part of the permanent bracing structure passing through said side walls over said bottom and partition and having its ends twisted together under tension.

In testimony whereof I affix my signature.

OSCAR WILLIAM ANDERSON.
